CLAIM

The ornamental design for a float or the like, as shown and described.

DESCRIPTION

FIG. 1 is a top plan view of a float or the like showing my new design, the bottom plan view being a mirror image of that shown;

FIG. 2 is a side elevational view thereof, the opposite side elevation view being a mirror image of that shown;

FIG. 3 is a front elevational view thereof; and

FIG. 4 is a rear elevational view thereof.

FIG. 1

FIG.3
